UNITED STATES PATENT OFFICE.

CHARLES SUMNER HINDS, OF FACTORYVILLE, PENNSYLVANIA.

DESIGN FOR A GAME-BOARD.

SPECIFICATION forming part of Design No. 29,747, dated November 29, 1898.

Application filed November 5, 1898. Serial No. 695,624. Term of patent 7 years.

To all whom it may concern:

Be it known that I, CHARLES SUMNER HINDS, a citizen of the United States, residing at Factoryville, in the county of Wyoming 5 and State of Pennsylvania, have invented and produced a new and original Design for a Game-Board, of which the following is a specification.

This invention relates to a new and original design for a game-board; and it has for its object to provide a design of this character which shall be both useful and ornamental.

The leading feature of the design resides in 15 a game-board having a flat surface divided into three adjoining oblong fields, the oppositely-located duplicate side fields being of a uniform checkered configuration with rows of alternating light and dark squares, and the 20 central field, which separates the side fields, having rows of light and dark squares, certain of which are grouped together at intervals to form in the dark shades of the squares prominent L-shaped and oblong figures.

25 In the drawings, Figure 1 is a plan view of a game-board embodying the herein-described design. Fig. 2 is a cross-sectional view of the game-board.

Referring to the drawings, the numeral 1 30 designates a game-board of a rectangular form and having on one side thereof a flat playing-surface 1^a. The flat playing-surface 1^a of the game-board is also rectangular in outline and is divided into three adjoining 35 oblong fields, (designated by the numerals 2, 2^a, and 3, respectively.) The oblong fields 2 and 2^a are the marginal fields of the game-board and are duplicates in appearance or

design, being of a uniform checkered configuration with rows of regularly-alternating 40 light and dark squares 3 and 4, respectively, it of course being understood that said squares 3 and 4 of the regularly and uniformly checkered fields 2 and 2^a are given a relatively light and dark appearance by any 45 suitable colors.

The oppositely duplicate checkered fields 1 and 2 are separated by the intermediate or central field 3, which central field is also provided with rows of light and dark squares 5 50 and 6, respectively, which light and dark squares in each row of the central field 3 also bear an alternate relation. Certain of the light and dark squares 5 and 6 within the central field 3 are grouped together at intervals, and this grouping of said squares produces in the dark shades 6 prominent L-shaped and oblong figures.

The playing-surface 2 of the game-board is provided with the three adjoining fields 2, 2^a, 60 and 3 to indicate the ground covered by opposing military forces, the fields 2 and 2^a being indicative of the original positions of the forces and the central or intermediate field 3 being indicative of the battle-ground. 65

What is claimed is—

The design for a game-board, herein shown and described.

In testimony that I claim the foregoing as my own I have hereto affixed my signature in 70 the presence of two witnesses.

CHARLES SUMNER HINDS.
